UNITED STATES PATENT OFFICE.

JAMES A. VARNUM, OF BOSTON, MASSACHUSETTS, AND ALBERT C. WARREN, OF NEW LONDON, CONNECTICUT.

DESIGN FOR A GAME-BOARD.

SPECIFICATION forming part of Design No. 32,262, dated February 20, 1900.

Application filed January 26, 1900. Serial No. 2,919. Term of patent 7 years.

To all whom it may concern:

Be it known that we, JAMES A. VARNUM, a resident of Boston, in the county of Suffolk and State of Massachusetts, and ALBERT C. WARREN, a resident of New London, in the county of New London and State of Connecticut, citizens of the United States, have invented and produced a new and original Design for a Game-Board, of which the following is a full, clear, and exact description.

Reference is to be had to the accompanying drawing, forming a part of this specification, in which the figure of the drawing is a plan view of a game-board, showing our design.

The leading feature of the design for a game-board consists of an octagon, arranged within the outline of which is a border forming the outline of a cross, and arranged within this outline are a number of squares alternating

in color, while perforations are arranged at 20 the corners of the squares.

A minor feature consists in making the portions of the base at the outer side of the cross-forming border of a color contrasting with the border. 25

Having thus described our invention, we claim as new and desire to secure by Letters Patent—

The design for a game-board, as herein shown and described. 30

In testimony whereof we have signed our names to this specification in the presence of two subscribing witnesses.

JAMES A. VARNUM.
ALBERT C. WARREN.
